AMUSEMENT APPARATUS

Frederick Cicero Twist, Weldon, Ill.

Application September 1, 1939, Serial No. 293,093

8 Claims. (Cl. 272—54)

This invention relates to improvements in amusement apparatus of that type, specifically, usually known as, and given the name of "teeter-totter."

The main object of the invention is to provide a structure of a type or form in which the teeter-board in its teetering movements is caused to partake of an ascending action and which, upon reaching a predetermined height returns to its normal low or starting position.

Another object lies in furnishing a standard having steps arranged in vertical order and to associate therewith a "teeter-board" provided with a pair of spaced pawls, one at each side of the standard, all being so arranged that in its teetering movement, due to alternate engagement of the pawl, the board will be made to "walk" or "climb" up such standard.

Further, that when the board has reached a predetermined height it will automatically reverse its movement and by gravity "walk" down said standard to its normal or starting position.

In addition to the above objects the invention lies in certain details of construction and in arrangement of parts to be brought out herein and form the subject of some of the claims to follow, it being understood that while certain structures are shown and described it is not the intention to be confined to such structures in bringing about the result sought, since equivalent ways may be provided such as would fairly fall within the meaning of the claims.

To the end that the invention may be clearly understood the accompanying drawings are provided forming part hereof.

Figure 1 is a side elevation of an apparatus involving the invention, showing two positions of an operating part thereof;

Figure 1^a illustrates in perspective a top structure of a portion of a support or standard of the apparatus, shown in Figure 1, and bracing parts therefor;

Figure 2 is a plan of the apparatus according to said Figure 1;

Figure 3 illustrates in perspective the pawl arrangement shown in Figure 2;

Figure 4 is a rear view in elevation of a teeter-board seat showing certain parts in cross section;

Figure 5 is a plan of parts shown in Figure 3 together with a standard and other parts entering into the invention;

Figure 6 is an elevation of part of a standard shown in Figure 5, in part section on line 6—6 of that figure, together with associated parts of the apparatus;

Figure 7 is a horizontal section of parts taken on line 7—7 of Figure 6;

Figure 8 is an elevation of parts shown in Figure 7 as seen from another side or as viewed by rotating the said parts as shown in said Figure 7 through an angle of 90°;

Figures 9, 10, and 11 show in perspective parts illustrated in Figures 6 and 8 separated from each other;

10 Figures 12 and 13 are elevations of a support or standard and pawls shown in earlier figures, together with parts shown in section, the whole illustrating pawl positions at said standard;

15 Figure 14 is a plan in detail of a spring and a carrier therefor, and

Figure 15 is a side elevation of some of the structural parts of Figure 1 showing added parts as a slight modification of the apparatus, for a purpose to be made known.

20 The purpose of the invention, briefly, is to provide a "teeter-board" as it will be termed herein that through effort of the riders stationed thereon, in bringing about a teetering or rocking motion, will cause the same to be gradually raised

25 step-by-step to any desired height above the ground by a pair of pawls or dogs engaging, alternately, certain steps arranged in vertical line upon a support. Further, to provide means whereby upon reaching any given height a shiftable mechanism will be automatically operated

30 so that the pawls or dogs will be so affected that a control means will admit of the teeter-board returning to the starting position by gravity step-by-step, whereupon the said mechanism will be shifted to restore the pawls to position for a second "climbing" operation.

In Figures 1 and 2 of the drawings 1 designates a supporting frame for the apparatus, suitably braced and which may include a central

40 member 2 upon which is supported an upright support or standard 3, the upper end of the latter being braced by frame portions 4 affixed to a top bar 5 and to said frame 1.

The support or standard 3 in this instance is shown as of channel form, the central web of which, as noted in Figures 1 and 1^a, is fabricated to form a series of steps 3' alternating in positions, laterally, one above the other and extending substantially the full length or height of that

50 member, all of said steps not being shown, however.

Mounted to move vertically upon the support 3 is a slide consisting in this instance of a pair of bars 6, Figure 10, particularly, also Figures 3 and 5, said bars lying one at each of two opposite

sides of the said support, Figures 5 and 7, the whole being supported by certain pawls engageable with the steps 3' as will be presently understood. Pivotally mounted at each bar 6 is a member 7, Figures 5 and 8, as will appear.

In the present instance the bars 6 lie upon the flanges of the support 3 and each carries a roller 8 within said channel to engage the walls of the same.

Each member 7 is suspended from a bar of a pair of members or bars 9 of some considerable length as part of the teetering structure, said bars rocking with the members 7, the latter pivoting on bolts 7' which carry the named rollers 8.

Hung from each of two tie rods 10 extending from one member to the other are two pawls 11 free to swing thereon and spaced from each other, the support 3 lying between them. On each rod is a coil spring 12, in this instance only, so mounted and controlled that one end thereof in bearing against a pawl will maintain such pawl yieldingly in the direction of said support 3 in order to engage any one of the steps 3' of the latter during teetering movement.

In addition to the bars 9 a pair of companion bars 9' is provided spaced downwardly from said bars 9, opposite ends of all of the bars having pivotal relation with a supporting member 13 a pair of seats 14, it being noted that the upper and lower bars, 9, 9' are cross connected to create a rigid trussed frame structure, all of course being by preference.

Spaced below this described frame-structure is a pair of bars, or levers, 15, one at each of two opposite sides of the support 3 and each pivotally supported at its middle on one of the previously named vertically shiftable bars 6, the ends of the bars or levers 15 pivotally supporting the lower ends of the seat supporting members 13 just mentioned, the latter being adjustable along the parts 9 and 9' and lever 15, if desired, to afford means of balancing the weights of riders.

The structure made up of the bars 9, 9', 15 and the seats 14 now comprise what I term the "teeter-board," it being observed that the extremities of the bars 15 extended beyond the seats, carry suitable cross strips 15' answering as floorings for occupants of the apparatus.

It is observed, further, that in the horizontal positions of the bars 9, 9' and 15, Figure 1 the seats 14 each stand substantially upright, since the distance between the point of pivotal support of bars 9 and 15 to the seat supporting member 13 are the same. However, since the said bars 9 and 15 swing upon widely spaced pivot points their ends will describe different arcs and thus the seats will be tilted toward and away from each other, Figure 1, for a purpose to appear in the description of the operation.

Shiftable vertically upon the support 3 besides the members 7 is a structure, Figure 9, including two spaced members or plates 16 connected at their upper ends for example to maintain their substantially fixed relation. Each of these said members or plates lies on the said support 3 facing the named steps 3' as shown in Figures 5 and 6 for example, and each has a slot 16' through which extends one of the pawls 11, see Figures 9, 12 and 13, while at the lower extremity of each plate in said Figure 9 is an outwardly extending lug 17. The relation of the bar 6 and one of the members or plates 16 is perhaps best shown in Figure 6. In this figure and in Figures 7, 8 and 11 is illustrated a fur-

ther structure including a pair of spaced plates 18 which in this instance have upper and lower extended ears 19, one of the plates also having a stud 20 projecting therefrom. This structure encloses the lower extremities of the bar 6 and is slideable vertically upon the same, the plates being connected by bolts 21 extending through the lugs 19, said bolts lying outward from and paralleling the plates 16.

10 It is noted that the lower end of one of the bars 6, Figure 10, has extended lugs 6' and that these, as shown in Figure 8 lie opposite the recesses created between the lugs 19 of the plates 18 and each carries a stud 6''. Two springs 16' are attached to and extend between, the ears 17 and the lower bolts 21 for example.

Assembled as in said Figure 8 coil springs 22 and 23 are carried at one of their ends on the studs 6'' their other ends being carried by the 20 stud 20 which is common to both said springs. The springs are under compression and, as shown in Figure 14, each may enclose a pair of overlapping strips 24, the latter preventing collapse thereof.

25 Near the upper end of the support 3 is a stop-member such as a clamp 25, Figure 1, or it may be a pin 26, Figure 15. Also near the base of said support may be any suitable stop-member such as a pin 21. The purpose of said stops will appear in the following.

30 In normal "standing" position or that position most convenient of access, of course, the teeter-board may be at the lowermost position at the support 3. At this time it may be stated that 35 in the ascending movement of the "board" the slotted plates 16 have no office but that in the descending movement they are caused to affect the pawls in a manner to be explained.

35 In starting, the occupant of the highest seat, 40 see dotted lines at the right of Figure 1, finds himself tilted forward toward the raised foot platform at his said seat. At this time, see Figure 12 at the left, his pawl will be in engagement with a step 3'. Now with his feet on his said 45 platform by exerting pressure thereon by straightening his limbs, with his back against the seat-back, the resultant leverage applied causes the board to be swung downwardly on its two pivots, the same being thereby lifted due to resting upon the named pawl. The opposite end of the board is thus raised, of course, and with it is carried the opposite pawl to a new position or step higher than that of the pawl first described, 50 whereupon the occupant of the thus raised board-extremity applies a like effort thus accomplishing a lifting of the said first pawl, with a further lift of the board to a new height.

55 At the right in Figure 12 just referred to, the pawl 11 is in the act of being lifted with the bars 60 9 as the latter tilt upwardly at that side of said figure. Said pawl is about to approach and rest upon a next higher step 3', or that next above the one upon which the left-hand pawl is resting as a support for a further climb of said bars.

65 Continued action finally brings the board to any highest position predetermined by the position of the stop-member 25 or 26, such member lying in the path of travel of one or the other or both plates 16 carrying the plates 18 of Figures 8 or 11. In the ascending travel the toggle made up of the spring arrangement 22-23 has the raised position shown in Figure 8 and during such time the pawls 11 have been free to have their step-by-step action through the slots 16' of the plates 16.

Upon plates 16 meeting the stop 25 in the continued upward movement of the board, the plate structure 18-18 is shifted to an opposite or low position on the members 6, the toggle swinging past center downwardly, see dotted lines in Figure 8.

Upon descending to a low position the plate-structure 18 strikes the lower stop 27 thus automatically allowing the pawls to be free of the plate 16 by relieving the pull upon the spring 16². At this time the riders or occupants of the board by their alternately applied efforts may repeat the upward climb.

It is to be understood that as the upper stop 25 is reached by the plate 16 the continued effort of the riders in the climbing act causes the plate structure 18 to be shifted downwardly due to the plates 16 striking said stop. The ears 17, Figure 8, strike the upper bolts 21, Figure 11, forcing the structure 18-18 downwardly changing the relation of the pawls at the steps 3', whereas at the lower position the teeter-board structure due to its weight shifts and moves downwardly through the plate structure when the latter meets the stop 27, said plate structure thereby shifting with respect to the plates 16, again changing the pawl relation. Of course, the plate structure could also strike the lower frame 1 in the downward movement, and the plates 16 could strike the upper frame portion at 4, 5 in the upward travel, all with the same result, i. e., the reversal of teeter-board travel. It may be stated that the springs 16² connecting the plates 16 with the plate structure 18-18 are merely strong enough to carry the weight of the latter yet permitting the shift of the same downwardly.

The upper and lower stop-members 25 and 27, respectively, may be adjusted to permit operation between any predetermined limit. Most naturally, the upper stop will be that most likely to be adjusted, especially when, for example, very young riders are to make use of the apparatus where a limit in height of travel is desirable as a safety measure.

In Figure 1 the seats are shown facing outwardly or so that the riders face in opposite direction. This is done to the end that the efforts of such riders will be most easily applied for leverage purposes in operating the apparatus. In Figure 15, however, the seats may face each other. When so placed an arrangement is provided for operating the board otherwise than previously stated. That is to say, arms 28 may be secured upon a traveling part of the apparatus such, for example, as the plate a in the figure named, said plate corresponding to a bar 6 of the form shown in said Figure 1. Each arm extends to a position above a seat and a rope depends from each, but one being shown.

This is merely a preferred manner of suspending the ropes in that such ropes, with the arms, travel with the balance of the arrangement.

In the use of this form or arrangement the rider who is lowermost brings about the rocking movement of the board by a pull on the rope.

The drawings show two ways of constructing the apparatus but naturally other ways are open for bringing about the end sought.

Due to the arrangement of the parts of the structure the teeter-board can remain at rest at any height since one or the other of the pawls 11 is in engagement with a step 3', provided that the up and down swinging movement of the teeter-board is limited to prevent the opposite pawl from engaging the next higher step 3', but the

riders may start operating the board to climb higher until, having reached the highest point, the automatic change in pawl relation will at once result in the descending action already described.

During the "climbing" action the springs 16² connected to and between the ears 17 of the plates 16 and the bolts 21 of the structure 18 have exerted no pull upon said plates since said ears have been resting upon said bolts holding the plates in raised position clear of the pawls 11.

The toggle, however, having been reversed as last above explained has resulted in lowering the structure 18 thus moving its bolts 21 away from the ears 17 allowing the spring 16² to act for the purpose of maintaining a downward pull on the said plates 16 so as to be in position at their edges, at the upper limit of the slots 16', to engage the pawls. Said plates as a unit now follow down as the structure 18 descends with the bars 6.

When, now, a pawl on a step 3' is supporting the weight of the teeter-board the plate 16 rests upon such pawl. In a succeeding upward tilt of the board opposite that pawl the weight is taken from the opposite pawl in the upward movement thereof releasing such opposite pawl which, due to the position of the plate is held away from the said support 3 and drops to a next lower step 3' in the lowering movement, each pawl acting in this manner.

For this reason the pawls being alternately held outwardly cannot engage a next step above but must drop to a step below instead. As the bars 6 descend step-by-step with the teeter-board's weight the plates 16 follow step-by-step due to the position pull of the springs 16² thereon and since the plates are fixed relatively they both move at the same time. When one of them engages a pawl that member is withdrawn from a step as the weight of the board is transferred therefrom to the opposite pawl during the rocking movement, consequently in the next rocking movement the first pawl named must drop to a next lower step. Thus the board in effect is dropped step-by-step reaching the limit of downward travel wholly by gravity action, no effort of the riders being required. Stated in another way, as a pawl is held outwardly the board-end adjacent thereto rocks downwardly until the opposite pawl is released whereupon the board descends at that side, and so on, the pawls being the pivot members upon which the structure rocks and about which it swings.

While springs have been described and shown as the means for controlling the pawls 11 and other parts herein, it is to be understood that other means for the several purposes may be substituted.

I claim:

1. In an amusement apparatus, a structure including an upright support, a second structure adapted for raising and lowering shifting movement with respect thereto, a teeter-board pivoted at its middle on the second named structure and maintained in a fixed vertical plane in its shifting movement with the latter, a pawl carried by said teeter-board at each side of the pivot point thereof, and a stepped portion carried by the first named structure with which the pawls alternately engage in the rocking movement of said teeter-board in either direction of shifting movement of said second structure.

2. In an amusement apparatus, a structure including a substantially upright support having a series of steps arranged one above the other, a

structure guided thereon in a fixed vertical plane adapted for a raising and lowering movement thereon, a teeter-board pivotally carried by the second named structure, and a pawl pivotally carried by said teeter-board at each side of the pivot point thereof, each normally held elastically in the direction of the named steps, the pawls being alternately lifted in the rocking movement of said board to engage a next higher step and alternately constituting a separate pivoting member and support for said board, and mechanism carried by the second named member to engage and prevent engagement of the pawls alternately with certain of the steps during one direction of travel of said second structure.

3. In an amusement apparatus, a structure including a substantially upright support having a series of steps arranged vertically thereon projecting alternately from opposite sides thereof, a structure guided on the support adapted for a raising and lowering movement, a teeter board pivotally carried by the second named structure, a pawl pivotally carried by the teeter-board at each side of the pivot of the same, each normally held elastically in the direction of and adapted to engage a step, the pawls being alternately lifted in the rocking movement of the board whereby each will engage a next higher step, each pawl constituting a support for the board and the pivot member upon which the same swings in alternate manner, mechanism carried by the second named member to engage and prevent engagement of the pawls alternately with certain of the steps during one direction of travel of said second structure, said mechanism being shiftable with respect to the latter, and a stop on the first named structure to receive said mechanism against it.

4. In an amusement apparatus, a structure including a substantially upright support having a series of steps arranged thereon one above another at opposite sides thereof, a second structure guided on the support for vertical movement in either of two directions, a teeter-board pivoted on said second structure, a pawl pivotally carried by the teeter-board at each side of the pivot thereof, each elastically controlled and adapted to move toward and engage upon a step during the rocking of said board, a third structure carried by and shiftable with respect to said second structure including a part to be brought into the path of movement of either pawl to prevent engagement with other than alternate steps during one direction of travel of said second structure, a shiftable fourth structure in control of the said third structure for shifting the same in either direction, and a stop at each extreme of travel of said third structure with which that structure engages.

5. In an amusement apparatus, a structure including a support having a series of steps arranged one above another, a structure adapted for raising and lowering movement with respect to the support, a rockable teeter-board pivoted

on the second named structure, a pawl pivotally carried on the board at opposite sides of the pivot of said second named structure, each adapted to engage and bear upon a step and therethrough 5 elevate the board during its rocking movement, means for directly controlling the pawls, mechanism on said second named structure adapted to directly act upon said means, and a stop member in the path of travel of said mechanism for shifting the same for changing the relation of said means to said pawls to effect a reversal of travel 10 of the said board.

6. In an amusement apparatus, a structure including a support having a series of steps arranged at opposite sides thereof in vertical order, a structure adapted to travel vertically at said support, a teeter-board pivotally mounted on the second named structure, a pawl pivoted on the board at each side of the series of steps, each 15 pawl separately adapted to engage upon a step in the rocking movement of the board to effect a climbing action of said board, means to control the relation of movement of the parts with respect to the step, a stop-member on the support, 20 and shiftable mechanism carried by said second named structure to engage the stop-member to bring about a reversal of lineal travel of the board with respect to the said support.

7. In an amusement apparatus, a structure including a support having a series of steps arranged at opposite sides thereof in vertical order, a structure adapted to travel in a vertical line on said support, a teeter-board pivotally mounted on the second named structure, a pawl pivoted on the board at each side of the series of steps adapted 30 separately to abut upon a step in the rocking movement of said board to effect a climbing action of the latter, a stop-member on the support, 35 and shiftable mechanism carried by the said second named structure to engage the stop-member during the lineal travel of the board, and means in control of the pawls to change their relation to the steps during action, and changed in such relation by said mechanism when the latter meets 40 said step-member whereby to bring about a reversal of such lineal travel of said board.

8. In an amusement apparatus, a structure including an upright support having a series of steps arranged in vertical order thereon and extending laterally from each side thereof in alternate order, a structure mounted to have linear movement along said support, a teeter-board pivoted on the second named structure, a pawl pivoted on the board at each side of the support, the 50 pawls being elastically held in the direction of the steps and adapted to separately and successively abut upon a step in the rocking movement of said board, a shiftable plate for the control of each pawl, shiftable mechanism to shift the plates with respect to the pawls, and a stop-member in the path of the mechanism to engage and bring about the shifting of the same.

FREDERICK CICERO TWIST.
